(57) **CLAIM**

The ornamental design for a tamper evident carton, as shown and described.

DESCRIPTION

FIG. 1 is a perspective view of a tamper evident carton showing a new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plane view thereof;

FIG. 7 is a bottom plane view thereof;

FIG. 8 is another perspective view of the tamper evident carton of FIG. 1 shown in a closed configuration;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plane view thereof;

FIG. 14 is a bottom plane view thereof;

FIG. 15 is another perspective view of the tamper evident carton of FIG. 8 shown with a tamper evident strip partially removed; and,

FIG. 16 is a top plane view of the tamper evident carton of FIGS. 1 and 8 shown in a flat unfolded configuration.

In the drawings the dash-dash broken lines in FIG. 15 depicting a hand are for the purpose of illustrating environment only and form no part of the claimed design.

1 Claim, 13 Drawing Sheets
